UNITED STATES PATENT OFFICE.

EDWARD TODD, JR., OF NEW YORK, N. Y.

DESIGN FOR A TUBING FOR PENCIL-BARRELS, &c.

SPECIFICATION forming part of Design No. 31,579, dated Oct. 1, 1899.

Application filed June 20, 1899. Serial No. 721,250. Term of patent 14 years.

To all whom it may concern.

Be it known that I, EDWARD TODD, Jr., a citizen of the United States, residing at New York, in the county of New York and State 5 of New York, have invented and produced a new and original Design for Tubing for Pencil-Barrels or Similar Articles; and I do hereby declare the following to be a full, clear, and exact description of the invention, such as 10 will enable others skilled in the art to which it appertains to make and use the same.

In the drawings, Figure 1 is an elevation of a piece of tubing, showing my new design. Fig. 2 is a cross-section of said tubing.

15 As shown in the drawings, the leading feature of my design is a tube having a polygonal exterior, with a row of semispherical beads

along the middle of each of its sides. Such tubing is available for a pencil-barrel and it can also be used for a variety of similar purposes.

Having thus described my invention, what I claim, and desire to secure by Letters Patent, is—

The design for tubing for pencil-barrels or 25 similar articles, substantially as herein shown and described.

In testimony whereof I affix my signature in presence of two witnesses.

EDWARD TODD, JR.
